UNITED STATES PATENT OFFICE.

FRANK B. CROSIER, OF UNIVERSITY, MISSISSIPPI, ASSIGNOR OF ONE-HALF TO
ARTHUR BOONE CROSIER, OF UNIVERSITY, MISSISSIPPI.

SOUND BOX AND ATTACHMENT.

Application filed May 5, 1921. Serial No. 467,021.

To all whom it may concern:

Be it known that I, FRANK B. CROSIER, a citizen of the United States, residing at University, in the county of Lafayette and State 5 of Mississippi, have invented certain new and useful Improvements in Sound Boxes and Attachments; and I do declare the following to be a full, clear, and exact description of the invention, such as will enable 10 others skilled in the art to which it appertains to make and use the same.

This invention relates to an improved attachment for sound boxes of the type used in association with sound reproducing machines such as phonographs and the like, although, it is not to be restricted to this 15 particular use.

More specifically speaking, I aim to provide a novel attachment of the class described 20 which has considerably more mass than the vibrating bar on which it is supported, the device functioning as a weight to such an extent that the inertia of the system is increased, thus absorbing a great deal 25 of the energy and inhibiting to a corresponding degree the vibratory action of the vibrating bar, whereby to obtain the result specified.

In the accompanying drawings forming a 30 part of this specification and in which like numerals are employed to designate like parts throughout the same:

Figure 1 is a side elevational view of one embodiment of the aforesaid device constructed 35 in accordance with this invention, showing the same attached to a sound box, the housing for the casing being shown in section.

Figure 2 is a top plan view thereof with 40 the casing in section.

Figure 3 is a sectional view taken substantially on the plane of the line 3—3 of Fig. 2.

Figure 4 is a view similar to Fig. 1 disclosing 45 a different embodiment of the invention.

Figure 5 is a top plan view thereof.

Figures 6 and 7 are sectional views taken substantially on the planes of the lines 6—6 and 7—7 respectively of Fig. 4.

Figure 8 is a detail perspective view of the 50 device with the casing removed.

Figure 9 is a view similar to Fig. 4 disclosing still another modified form of the invention.

Figure 10 is a view approximating that

shown in Fig. 9 disclosing a slightly different embodiment of the invention.

Figure 11 is a view simulating Figs. 9 and 10 showing a further modification of the invention.

Figure 12 is a sectional view taken substantially on the plane of the line 12—12 of Fig. 11.

Since the general principle of operation involved is identical in all embodiments of the invention, I have grouped them in a logical order and will describe each embodiment separately.

For the purpose of enabling the reader to obtain a clear understanding of the invention, the same is shown in association with 70 a conventional type of sound box designated in all figures by the letter A. The construction of the sound-box is well known and by observing the drawings, it will be seen that the same includes a metallic vibrator B, a 75 stylus holder C in which the needle D is held, the latter being designed to travel in the usual undulations on the record to receive and transmit vibrations to the diaphragm E.

Referring now to the drawings and confining attention to Figs. 1 to 3 inclusive, it will be seen that the device here illustrated comprises a metallic frame 1 including a laterally directed portion 2 equipped at its free 85 end with a clamp 3 of any suitable construction, this clamp being designed for connection to the vibrator bar B at any suitable point. The frame 1 serves as a support for a suitably shaped resonant body 4 preferably in the form of a relatively thin board of vibrating material. In the present showing, the body is composed of a plurality of separate pieces or sections 5 of varying lengths which may be connected in any appropriate manner to the side bars of the frame. As will be observed, the sections 5 are spaced vertically from one another. At 90 its upper end, the frame is provided with a pair of spaced diverging arms 6 to which the free ends of a wire 7 are connected in any suitable manner. As better seen in Fig. 3, this wire is bent into V-shape and its ends secured to the ends of the arms 6 as indicated at 8, while the intermediate portion thereof has detachable connection with a hook 9 on the outer end of an arm 10 clamped or otherwise secured to the afore-

said vibrator bar B. In practice, a casing 12 is fitted onto the rim of the sound box and serves to cover and protect the attachment. Also, for the purpose of securing 5 better results, I provide this casing with an opening in one side and project a tension member 11 therethrough to engage one of the divergent stretches of the aforesaid wire.

Referring now to Figs. 4 to 8 inclusive, 10 another embodiment of the invention will be seen. Here, the body is likewise in the form of a board 14, but instead of being composed of the sections of varying lengths as before described, it is in one-piece. This 15 body is likewise adapted to be disposed in spaced parallelism with the diaphragm of the sound box. Connected to the board 14 by means of a screw 15 is a second and smaller board 16 which may be conveniently 20 referred to as an auxiliary board, the same serving to add more mass to the structure and to absorb vibrations to a more pronounced degree. This board 16 is connected to the bar B through the medium of an attaching arm 17 equipped with a detachable 25 clamp 18. If desired, a small rubber sleeve 19 may surround the screw 15 to act as a spacer between the two boards. This embodiment of the invention, like the one already 30 described, includes an arm 20 which is detachably clamped to the vibrator bar as indicated at 21 and this arm is formed at its outer end with a hook 22 which is engaged with the intermediate portion of the 35 wire 23 which is also bent to assume the shape shown and has its opposite free ends connected to the board 14 by means of screws or their equivalents 24. Rubber sleeves 25 are also employed to surround the screws 40 24. This form of the invention also includes a tension device or member 26 for one stretch of the wire and further includes the protecting housing or casing 27.

Confining attention now to Fig. 9, it will 45 be seen that the device here shown is a substantial duplicate of the one just described with the exception of the wire and tension device associated therewith, these parts being omitted, and the arm 20 being directly 50 connected to the lower central portion of the board as shown. The analogy of these two forms of the invention permits the same reference characters to be used to designate all like parts.

55 The embodiment of the invention disclosed in Fig. 10 is quite similar to the one shown in Figs. 4 to 8 inclusive with the exception that the auxiliary board is omitted, the attaching arm 17 employed to connect said board to the vibrator bar, being directly connected to the lower central portion of the main board as indicated at 30.

In addition to the embodiment of the invention already described, there is still another embodiment shown in Figs. 11 and 12.

Confining attention to these figures, we observe that 31 designates a substantially disk-like board which is arranged in parallelism and spaced from the diaphragm of the sound box, being held in this position by means of an arm 33 having a clamp 34 detachably connected with the vibrator bar. A substantially semi-cylindrical metallic screen 35 is connected in any appropriate manner to the outer face of the board and is preferably supported in the proper position by means of a curved arm or its equivalent 36 which is connected therewith and detachably connected at 37 with the vibrator bar. The elastic character of the screen serves further to impede the movement of the vibrating bar on its fulcrum and adds the desired mass to this embodiment of the invention. If desired, a casing or housing 38 may be employed here.

85 In use, the invention simply provides a structure that has much more mass than the vibrating bar upon which it is mounted. Hence, it functions as a weight to such an extent that it increases the inertia of the 90 system. Thus, much of the energy of the system will be absorbed and the vibratory action of the bar B will be inhibited to a corresponding degree and the use of such a device will be found as a material asset 95 to tone betterment. The principle of operation, as before stated, of all of the embodiments of the invention is the same.

I claim:

1. A device of the class described comprising an attachment for the vibrating bar of a diaphragm, said attachment embodying a horizontally disposed arm connected to said bar, a substantially V-shaped wire, the intermediate portion of which is connected with the free end of said arm, and connections between the ends of said wire and said vibratory bar.

100 2. The structure specified in claim 2; together with a tension device supported adjacent said wire to engage at least one stretch thereof.

105 3. A device of the class described comprising an arm adapted for connection to the vibrating bar of a diaphragm, a substantially V-shaped wire having its intermediate portion connected to the free end of said arm, and a vibratory body connected with said bar, the free ends of said V-shaped wire being in association with said body.

115 4. A device of the class described comprising an arm to be connected to a vibrating bar of a diaphragm, a body adapted for disposition in spaced parallelism with respect to said diaphragm, a connection between said body and said bar, and means between the free end of the aforesaid arm and said body for adding more mass to the structure.

120 5. An attachment for the diaphragm vi-

- brating bar of a sound box comprising a body of vibrating material, said body being composed of a plurality of vertically spaced sections and being adapted to be disposed in spaced relation with respect to the diaphragm, and an arm connected to said body and extending laterally therefrom for supporting the body on the bar to increase the inertia of the system.
- 10 6. A device of the class described comprising a frame adapted to be supported on a diaphragm vibrating bar, a plurality of vertically spaced members carried by said frame, said members being of varying lengths.
- 15 7. A device of the class described com-
- prising a frame adapted to be supported in spaced parallelism with respect to the diaphragm of a sound-box, means for supporting said frame from a vibrator bar of 20 the diaphragm, said frame including a pair of spaced arms at its top, a plurality of vertically spaced members of vibrating material carried by said frame, a horizontally disposed arm adapted for connection to the 25 aforesaid bar, and a wire connected with said arms and with the aforesaid diverging arm.

In testimony whereof I have hereunto set my hand.

FRANK B. CROSIER.
